UNITED STATES PATENT OFFICE.

EMORY T. BOOTH, OF NEW YORK, N. Y., ASSIGNOR TO A. A. VANTINE & CO.,
OF NEW YORK, N. Y., A CORPORATION.

DESIGN FOR A BOTTLE.

No. 38,710.

Specification for Design.

Patented July 30, 1907.

Application filed June 28, 1907. Serial No. 381,377. Term of patent 7 years.

To all whom it may concern:

Be it known that I, EMORY T. BOOTH, a citizen of the United States, residing at No. 209 Macon street, borough of Brooklyn, city of New York, State of New York, have invented a new, original, and ornamental Design for Bottles, of which the following is a specification, reference being had to the accompanying drawing, forming part thereof.

The figure is a view of a bottle showing my new design as embodied therein.

I claim

The ornamental design for a bottle as shown.

EMORY T. BOOTH.
